poration of New York

Application October 29, 1951, Serial No. 17,146

Term of patent 14 years

(Cl. D83—1)

To all whom it may concern:

Be it known that I, Paul E. Roehrich, a citizen of the United States, residing in Rockville Centre, county of Nassau, and State of New York, has invented a new, original, and ornamental Design for a Dispensing Container for Fluid, of which the following is a specification, reference being had to the accompanying drawing, forming a part thereof, wherein:

Fig. 1 is a top plan view of a dispensing container for fluid showing my new design; and
Fig. 2 is a front elevational view thereof.

I claim:

The ornamental design for a dispensing container for fluid, substantially as shown.

PAUL E. ROEHRICH.
